UNITED STATES PATENT OFFICE.

GEORGE E. VOELKEL, OF LOS ANGELES, CALIFORNIA.

FIREPROOF FRAME BUILDING.

SPECIFICATION forming part of Letters Patent No. 710,307, dated September 30, 1902.

Application filed July 14, 1902. Serial No. 115,545. (No model.)

To all whom it may concern:

Be it known that I, GEORGE E. VOELKEL, a citizen of the United States, residing at Los Angeles, in the county of Los Angeles, State 5 of California, have invented certain new and useful Improvements in Fireproof Frame Buildings; and I do hereby declare the following to be a full, clear, and exact description of the invention, such as will enable others skilled in the art to which it appertains to 10 make and use the same.

This invention relates to fireproof buildings; and it has for its object to provide a structure in which the wooden frame will be 15 partly inclosed with fireproof material and in the building of which structure there will be provided means for ventilating and heating the walls.

Other objects and advantages of the invention will be understood from the following 20 description.

In the drawings forming a portion of this specification, and in which like numerals of reference indicate similar parts in the several 25 views, Figure 1 is an isometric view showing a portion of the building embodying the present invention. Fig. 2 is a vertical section through a wall of the building and illustrating the ventilating and heating provisions. 30 Fig. 3 is a transverse section through a wall of the building.

Referring now to the drawings, the wall proper or outer portions of the walls of the building are formed of concrete, which may 35 have an exterior facing of bricks, stone, or any other material desired.

The foundation-wall 5 is of any desired thickness, determined by the weight to be sustained, and at the top of the thickened 40 portion of the wall or foundation-wall is the wall-plate 6, on which the studs 7 are erected and on which they stand. Against the outer faces of the studs 7 are secured the boards 8, which extend throughout the length of the 45 studs and may be in suitable sections for convenience. The boards 8 project laterally beyond the side faces of the studs to form keys for the concrete work. The studs 7 are set 50 backwardly from the inner edge of the wall-plate, and against the inner faces of the studs is secured the ribbon-plate 9, on which the

floor-joists 10 rest. Upon the foundation-wall and the upper face of the wall-plate between the studs is built the concrete wall 11, the outer face of which lies beyond the boards 55 8, so that the boards and the side and outer faces of the studs are completely incased. The concrete wall 11 makes in this way a continuous fireproof shell or crust around the whole building, which is secured firmly to 60 the frame of the building. The inner face of the concrete wall is flush with the inner faces of the studs from the tops of the floor-joists to the wall-plate, while the wall above the joists is reduced in thickness, so that air-spaces 12 are formed between the inner face 65 of the concrete wall, the studs, and the inside plaster 13. The lathing for the inside plaster 13 is secured to the studs in the usual manner and extends down to the tops of the joists. 70 The air-spaces extend also down between the joists, said air-spaces being reduced in width, as shown at 14, and these reduced portions of the air-spaces which are between the joists have gratings 15 secured over them, so that 75 large particles of foreign matter will be prevented from entering the air-spaces. The air-spaces 12 permit a free circulation of air from the cellar to the attic of the house, so that the walls of the building may be cool in summer, 80 while in winter the house may be most effectively heated by connecting the air-spaces with hot-air pipes of the ordinary furnace. Furthermore, the walls may be cooled in summer by opening the windows in the cellar and attic 85 of the building and permitting air to pass through the passages. Upon the joists are secured the usual subfloor-planks 16, to which the floor-boards 17 are nailed and on which rests the usual base-board 18. 90

The studs of the corners of the building touch or may be spaced apart, as preferred, it being understood that in practice modifications of the specific construction shown may be made and that any suitable materials 95 and proportions may be used for the various parts without departing from the spirit of the invention.

What is claimed is—

1. A building comprising a concrete wall, 100 studs partly embedded in the inner face of the wall and boards secured to the outer faces

of the studs and completely embedded in the wall, the inner faces of the studs being exposed for attachment of laths thereto.

2. A building comprising a concrete wall, 5 studs partly embedded in the inner face of the wall and boards secured to the outer faces of the studs and completely embedded in the wall, the inner faces of the studs being exposed for attachment of laths thereto, the 10 upper portions of the studs projecting inwardly beyond the inner face of the wall to provide air-spaces between the studs, the wall and the lathing.

3. A building comprising a concrete wall, 15 having its lower portion of greater thickness than the upper portion and having a wall-plate embedded in the inner face of the thickened portion, studs each having a board secured to its outer face and projecting beyond

the side faces of the stud, said studs being 20 disposed upon the wall-plate with the boards and adjacent portions of the studs embedded in the wall, said studs extending inwardly from the inner face of the upper thinner portion of the wall, seats formed in the wall, 25 joists engaged in the seats and against the studs, an inner wall portion secured to the studs above the joists and separated from the outer wall portion by interspaces between the studs, and grates secured between the joists 30 and extending from the upper faces of the latter to the thicker portion of the wall.

In testimony whereof I affix my signature in presence of two witnesses:

GEORGE E. VOELKEL.
